DESIGN FOR A PEN NIB

Louis J. Weigel, Short Hills, N. J.

Application October 10, 1940, Serial No. 95,748

Term of patent 7 years

To all whom it may concern:

Be it known that I, Louis J. Weigel, a citizen of the United States and a resident of Short Hills, in the county of Essex and State of New Jersey, have invented a new, original, and ornamental Design for a Pen Nib, of which the following is a specification, reference being had to the accompanying drawing, forming part thereof.

I claim:

The ornamental design for a pen nib, as shown.

LOUIS J. WEIGEL.
